UNITED STATES PATENT OFFICE.

THOMAS E. McDERMOTT AND JOHN CAMPBELL, OF MINNEAPOLIS, MINNESOTA.

OAR-LOCK.

1,196,962.

Specification of Letters Patent. Patented Sept. 5, 1916.

Application filed March 10, 1915. Serial No. 13,397.

To all whom it may concern:

Be it known that we, THOMAS E. McDERMOTT and JOHN CAMPBELL, citizens of the United States, residing at Minneapolis, in the county of Hennepin and State of Minnesota, have invented certain new and useful Improvements in Oar-Locks; and we do hereby declare the following to be a full, clear, and exact description of the invention, such as will enable others skilled in the art to which it appertains to make and use the same.

Our invention has for its object to provide an extremely high and efficient oar lock which may be cheaply made from pressed metal.

Generally stated, the invention consists of novel devices and combination devices hereinafter described and defined in the claims.

In the accompanying drawings which illustrate the invention, like characters indicate like parts throughout the several views.

Referring to the drawings, Figure 1 is a view partly in side elevation and partly in vertical section showing the improved oar lock applied to an oar and seated in a press metal socket. Fig. 2 is a detailed view in plan showing a portion of an oar and the oar lock in which it is seated. Fig. 3 is a side elevation of the oar lock. Fig. 4 is an edge elevation of the so-called oar band of the lock showing the same with its sides pressed inward. Fig. 5 is a perspective view showing the oar band strung out, and Fig. 6 is a horizontal section taken from the line X⁶ of Fig. 1.

The oar lock proper comprises a fork 1, and a stem 2, both of which are integrally formed from pressed metal, preferably from sheet steel. The fork is channel shaped in cross section with the inner surface of the fork slightly rounded in cross section and with the channel on the outside of the fork. The stem 2, is formed by pressing extensions of the side flanges of the fork into semi-cylindrical shape and bringing these semi-cylindrical portions together to form the hollow cylindrical stem shown in the drawings. Approximately at the point where the stem joins with the flanges of the fork it has an enlarged shoulder or outstanding rib. The stem of the oar lock is adapted to be inserted into the usual or any suitable form of socket, but preferably said socket is

formed from a piece of channel shaped pressed steel 3, the web of which is cut and partly severed, and the partly severed portions 4, are bent to form an approximately 60 cylindrical socket adapted to receive the said oar lock stem.

An oar may be placed directly in the fork of the oar lock and the oar lock used in the usual way; and an oar lock thus formed 65 will be much lighter and yet stronger than the ordinary malleable cast oar lock. As an important feature of the oar lock construction, however, we have provided a so-called oar band. This oar band is preferably 70 constructed as follows, reference being had first to Fig. 5 wherein the numeral 5 indicates a thin flat spring steel bar provided at one end with a lock perforation 6, and at its other end with a latterly pressed lock 75 hook, 7. This spring bar 5, is adapted to be readily bent into annular form and to be secured into such form by inter-locking the hook or lug 7, with the lock perforation 6. The band forming bar 5, is provided with 80 projecting studs or trunnions 8, so spaced that when the band is formed they will project outward from the band at diametrically opposite points. A pliable facing or lining strip 9, of leather, or other suitable pliable 85 material, is secured to one face of the bar 5, so that it forms a liner for the oar band and is adapted to directly engage with the oar 10, when the latter is inserted through the band. Before the oar is inserted into the 90 said band, however, the trunnions of the band should be inserted into perforations or seats provided therefor in the prongs of the oar lock yoke 1. This may be easily done 95 by pressing the oar lock band into flattened form, (see Fig. 4), and then allowing it to expand back to annular form while the trunnions 8, are in position for entrance into their seats in said yoke. After this has been done the oar may be slipped endwise through 100 the band. Obviously, as long as the oar is in the band it will be impossible for the band to flatten, and hence its trunnions will be positively held into locks with the oar lock fork. The oar may be turned within the 105 band as required in the feathering stroke and the trunnions support the band and oar for free oscillations in the vertical plane. The oar cannot, of course accidentally jump out of the oar lock but can be detached 110 from the oar lock only by endwise movement. The oar lock described has the much desired

qualities of lightness, rigidity, good wearing qualities, small manufacturing cost, and high efficiency for the purposes had in view.

What we claim is—

- 5 1. A pressed metal oar lock having a fork that is channel shaped in cross section and having extensions from the intermediate portion of its side flanges bent to form the stem thereof.
- 10 2. A pressed metal oar lock having a fork that is channel shaped in cross section, with its flanges turned outward and with the intermediate portion of its flanges having integral extensions bent into approximately semi-cylindrical form, said cylindrical portions forming the stem of the oar lock.
- 15 3. A pressed metal oar lock having a fork that is channel shaped in cross section, with its flanges turned outward and with the intermediate portion of its flanges having integral extensions bent into approximately semi-cylindrical form, said cylindrical portions forming the stem of the oar lock, and the said stem having an outpressed stop shoulder close to the junction thereof with the flanges of said fork.

4. A combination with the fork of an oar lock, of an oar band made of a spring metal bar bent into annular form and having interlocked ends and provided with projecting trunnions adapted to be sprung into and out of pivot engagement with seats in said fork.

5. A combination with a pressed metal oar lock, channel shaped in cross section and having trunnion seats in its prongs, of a spring oar band with diametrically projecting trunnions adapted to be sprung into and out of pivot engagement with the seats in the prongs of said oar lock.

6. A pressed metal oar lock socket made from a channelled bar having a portion of its web cut and bent into approximately semi-cylindrical form and adapted to receive the stem of the oar lock.

In testimony whereof we affix our signatures in presence of two witnesses.

THOMAS E. McDERMOTT.
JOHN CAMPBELL.
